UNITED STATES PATENT OFFICE.

VICTOR SABLOVE, OF PHILADELPHIA, PENNSYLVANIA.

SKIRT, PETTICOAT, AND THE LIKE.

1,084,968.

Specification of Letters Patent. Patented Jan. 20, 1914.

Application filed September 27, 1912. Serial No. 722,568.

To all whom it may concern:

Be it known that I, VICTOR SABLOVE, a citizen of the United States, residing at Philadelphia, in the county of Philadelphia and State of Pennsylvania, have invented 5 certain new and useful Improvements in Skirts, Petticoats, and the like, of which the following is a specification.

My invention relates to improvements in 10 skirts, petticoats, and the like, the object of the invention being to provide an improved skirt which is adjustable to fit various sizes of waist and hips, so that the skirts may be manufactured of a uniform size and be adjusted 15 by the purchaser to exactly fit the wearer.

A further object is to provide a skirt 20 with an inside panel at the back which is formed integral with the body of the skirt at the waist and seat, which permits the skirt at the waist to be expanded forming a V at the back and provide improved snap button members at the waist line which engage any of a plurality of snap button members 25 on the panel, whereby the skirt may be adjusted to nicely fit the figure.

With these and other objects in view, the invention consists in certain novel features of construction and combinations and arrangements of parts as will be more fully 30 hereinafter described and pointed out in the claim.

In the accompanying drawings: Figure 1 is a view in rear elevation illustrating my 35 improved skirt adjusted to its smallest size. Fig. 2 is a similar view showing the skirt adjusted to its largest size. Fig. 3 is a fragmentary view in front elevation of the skirt with a portion of the front cut away to expose the panel in the rear of the skirt. Fig. 40 40 is an enlarged view in transverse section through the panel and the waist portion of the skirt. Fig. 5 is a fragmentary plan view of that portion of the skirt pattern 45 showing the construction of the rear of the skirt which forms a panel.

1 represents a skirt or petticoat, and while I shall term the same a skirt, it is to be understood that this term is used in its broadest 50 sense to include a petticoat or other article which is capable of a construction such as hereinafter described.

The back portion of the skirt is cut out in making the skirt in conformity with the 55 pattern such as shown in Fig. 5. The waist portion of the pattern is cut on a curved line

2, and the lower portion of the goods are cut on the lines 3, 3 and on the transverse line 4, so that when the edges 5, 5, are brought together, the surplus material between the dotted lines 7 and 8 will be folded inside the skirt to form an inside panel which extends from the line 9 to line 10, and the pattern preferably has a central fold line 11^a which may or may not be formed in the 65 goods.

When the rear of the skirt is cut out in conformity to the pattern shown in Fig. 5, and the goods pressed upon the lines 7, 8, 9, and 10, the outside edges of the skirt will 70 come together as shown in Fig. 1, hiding completely the inside panel illustrated by the reference numeral 11. The lower end of the material forming the panel is folded upon itself, and when the skirt is seamed 75 together, this folded portion is sewed to the body of the skirt by a triangular line of stitching 12 as indicated in Figs. 1 and 2.

It will be noted that the fold lines all taper so that they are closer together at 80 their lower ends than at their upper ends. This gives to the panel 11, a general triangular shape with the widest portion of the panel at the waist line, so that the skirt may be expanded at the waist line into general 85 V-shape at the back as shown in Fig. 2 to expose the panel.

On the waist band 12^a of the skirt, at both sides of the folded portion, snap button members 13 are located and along the upper 90 edge of the panel, a plurality of snap button members 14 are located to receive in any of them, the snap button members 13.

It is my intention to manufacture skirts which in the form shown in Fig. 1, are 95 adapted to fit the smaller sizes of women, and when in the shape shown in Fig. 2, the larger sizes, so that by adjusting the skirt and securing the snap button members 13 in the proper snap button members 14, the 100 skirt may be adjusted to fit any size. Furthermore, it will be noted that the adjustment of the waist line also adjusts the skirt over the seat and hips, so that the purchaser of a skirt may secure just the desired 105 fullness over the hips as well as at the waist line. It is to be borne in mind that the inside panel 11 forms an integral part of the goods of the skirt and hence the adjustment of the skirt does not disfigure the same in 110 the slightest because the skirt looks equally well in any adjustment.

Various slight changes might be made in the general form and arrangement of parts described without departing from my invention, and hence I do not limit myself to the precise details set forth, but consider myself at liberty to make such changes and alterations as fairly fall within the spirit and scope of the appended claim.

Having thus described my invention, what I claim as new and desire to secure by Letters Patent is:

A skirt having its rear section cut out at an intermediate portion at a point appreciably below its upper edge, and folded upon

diverging fold lines extending from said cut out portion to the upper edge of the section, whereby an inside integral panel is formed, and fastening devices on the waist portion of the skirt and upon the panel, substantially as described.

In testimony whereof I have signed my name to this specification in the presence of two subscribing witnesses.

VICTOR SABLOVE.
